United States Patent Office.

HORACE P. GALE, OF WASHINGTON, VERMONT.

Letters Patent No. 79,464, dated June 30, 1868.

IMPROVEMENT IN THE MANUFACTURE OF SUGAR.

The Schedule referred to in these Letters Patent and making part of the same.

TO ALL WHOM IT MAY CONCERN:

Be it known that I, HORACE P. GALE, of Washington, in the county of Orange, and State of Vermont, have invented a new and improved Method of Making Sugar from all substances of which sugar is made; and I do hereby declare that the following is a full and exact description thereof, reference being had to the accompanying drawings, and to the letters of reference marked thereon.

The nature of my invention consists in the peculiar combination of flues, dampers, stop-cocks, and smoke-stacks, by the use of which the desired effect is obtained in the art of making sugar, namely, the great saving of fuel, a great saving of time, a greater amount of sugar made from a given amount of the raw material, and a much superior article.

To enable others skilled in the art to make and use my invention, I will proceed to describe its construction and operation.

First, I construct my arch of brick, on a good stone foundation, nine feet square. I then build my arch three feet high, nine feet long, five feet four inches wide outside, with a wing on the right-hand side A, six feet three inches long, three feet eight inches wide, twenty inches high. Inside of the arch, I build three partitions, the first, lengthwise, twenty-five inches from the left-hand wall B, six feet six inches long, two feet six inches high, as shown in section 1, forming two compartments, one twenty-five inches wide, the other fifteen inches wide. I now place a transverse partition in the wide twenty-five inch space, three feet from the front wall C, twenty-two inches high; this forms my fireplace, three feet long, twenty-five inches wide, thirty inches deep, with door in front. I now place another transverse partition in the narrow fifteen-inch compartment, fifteen inches from the front wall C, and twenty-two inches high, forming a compartment at the right-hand corner of the fireplace, fifteen inches square and thirty inches deep. Back of this partition, around to the back of the other transverse partition, I fill with earth level with the top of each partition, forming a space, under the evaporator or pan, seven inches deep. I now place a long damper of cast iron, tightly fitting in a cast-iron frame, on the top of transverse partition at the back end of the fireplace, which will just fill the space between the top of the partition and bottom of the pan, closing the space perfectly tight at will. I now have a second damper, which is round or square, as I may choose, one foot, more or less, in diameter; this I place in the first long partition at the front end, as seen in section 1, at D. I now place a third damper, of the same style as the second, in the right-hand wall, four inches from the bottom, directly opposite the second, as shown in section 3, at E. I now have a smoke-stack, made of sheet iron, or any other material suitable, one foot, more or less, in diameter, as the case may require, and from nine feet high, more or less, with an elbow at the bottom, and a snug-fitting damper in the same, as seen at F, in perspective. This elbow passes through the front wall at the end of the narrow fifteen-inch compartment, eight inches from the top of the wall. I now place a grate in the fireplace, six inches from the bottom, as seen in section 2, at G. I now place a damper at the bottom of the left-hand wall B, at the farther left-hand corner of the fireplace under the grate. I now place a second smoke-stack, the same as the first, at the farther end of the wing part of the arch, as seen in perspective; this I place on cast-iron plate on the top of the wall, or put it through the wall with an elbow, it being optional, as seen at H. I now place a transverse partition in the wing, half way from one end to the other, thirteen inches high.

The arch completed, I now come to the evaporator or pan. This I construct of sheet iron, zinc, copper, or any other material suitable for the business, six feet eight inches long, four feet two inches wide, ten inches deep. Now I make nine holes, two inches in diameter, through the bottom of my pan, and the same through the end, five of them over the twenty-five-inch compartment, and four over the fifteen-inch compartment, as seen in section 4. The short flues which I insert in these holes, go through the bottom of the pan just back of the long damper, and the long flues pass down through the bottom at the front end, as seen in section 4. These flues all have an elbow at one end that passes down through the bottom. When they are properly adjusted, they are two inches from the bottom of the pan. These flues I make of tin or any other suitable metal. Now I insert at the front right-hand corner, on the side, a stop-cock, which will drain the pan without ever moving it from the arch.

I now proceed to set the pan in the arch. I set it down six inches in the arch, which rests it on the long partition, the long damper, and the one-and-a-half inch shoulder in the walls when built. I set the back end of the pan half an inch the highest to secure drainage. Now there is a space of one foot beyond the pan, which I cover with a cast-iron plate, as seen in perspective at I. Through this plate, two inches from the pan, I cut a hole six inches wide and thirty inches long, and over which I place a sheet or cast-iron box, nine inches wide, seven and one-half inches deep, thirty-one inches long, on the front of which I engrave the title, "King of the Forest." In this box, I place a pipe of metal that is shaped something like a kettle-bail. One end of this pipe passes through the end of the box, which connects with another pipe that leads to the sap-holder; the other end passes through the front plate, into which I insert a gauge-faucet, which empties into the pan.

Now the whole thing is built, I will proceed to the operation.

First. In making maple sugar, I would have my sap all strained when it goes into the holder, to free it from all impurities, that the sap may not be colored.

Second. I fill my pan till the flues are well covered, then I start the fire, of either wood or coal, open the long damper back of fireplace, and at the bottom of door, and in the smoke-stack F, also the gauge-faucet that supplies the pan. All is now in running order, with the fire passing under the pan and through the short flues to the hot-air chamber at the back end of the pan; then it is brought through the fifteen-inch compartment, and the long flues, to the smoke-stack F. Now it is well known to all men, and boys, that when the liquid is very sweet it does not evaporate half so fast. When it gets down to this state, I then open the stop-cock at the corner of the pan, and draw the syrup into the purifier or grainer in the wing, which is constructed of zinc or iron, five feet one and a half inch long, three feet wide, one foot deep, as seen in perspective at J, and set three inches deep in the wall.

I draw off till the flues in the pan are just barely covered, to prevent injury. Now I close the damper in the smoke-stack, at F, and open the damper E, as seen in perspective, and in section 3, and in smoke-stack, as seen at K. Now both pans are in full operation to the greatest possible advantage. As it evaporates in the grainer, I supply from the big pan, as seen at L. Now, then, I run it in this way till I wish to grain what I have in the grainer; then, if the fire is too strong for this part of the business, I open partly the damper, at F, in smoke-stack, and partly close the damper in smoke-stack, at K. I regulate the heat under the grainer at will.

The next operation is close by. The sap is nearly out of the big holder, and when it is, I disconnect the pipe from the holder to the heater, and take the heater off and set aside, cover up the open place with a cast or sheet-iron plate. Now, then, it soon boils down till the flues are nearly bare, then close the damper in the door, and open the one at the bottom of the wall under the grate, and the one in the long partition. Now I reverse my draught and fire, close the long damper, and the fire passes directly out of the smoke-stack, at F, or passes through to the other smoke-stack if wanted there, wholly at my will.

Now the sugar in the grainer is done. I take it out if I wish to put it into a tub for drainage; if not, I do it down dry for stirring into lumps, which I do before I remove from the grainer. This done, I repair for home with a big day's work done, and a beautiful article of sugar.

Now, gentlemen, if you could see and taste this sugar, as I do, you would detect no taste of buds, leaves, or barks, or bitter from scorching; nothing but a pure white beautiful article, which readily commands five dollars to the hundred pounds more than that made in the ordinary way, where it is full of soot, ashes, and all other impurities, black as tar, and about as good. I repeat, if you could see all this, as I do, I freely believe my prayer to you would be answered.

You will naturally inquire, is this all so? I answer, yes; first, because it is well known to many scientific farmers that the more rapid the evaporation is carried on, the better the sugar; in this you have it. Again, they understand that the longer the heat can be kept in the works, before reaching the smoke-stack, the less fuel it takes; in this you have it. Also, they know, to their sorrow, that it is extremely difficult to grain their sugar without scorching, on account of the blaze of the fire coming in contact with the bottom of the grainer; if this takes place, the sugar is surely scorched. But in this, all that very serious trouble is obviated. My grainer is so far from the fire that no blaze will ever enter the wing; nothing but heated air, and of that any amount I please. Again, I finish my sugar by the same fire that I boil it down with; hence, I make a great saving in fuel, and in the quantity of sugar, as the syrup shrinks two per cent. by standing over night.

The whole expense of graining is saved in this "King of the Forest," for it operates on time the same as on fuel; the same time that is required to evaporate does the graining.

What I claim as my invention, and wish to secure by Letters Patent, is—

The peculiar construction of the inside of my arch, arrangement of smoke-stacks, the application of flues in my pan, and the combination of dampers and stop-cocks to produce the advantages herein set forth.

HORACE P. GALE.
